OPERATING HANDLE FOR A BEVERAGE DISPENSER

Clare E. Hodgman, Mamaroneck, N. Y., assignor to The Coca-Cola Company, Atlanta, Ga., a corporation of Delaware

Application April 18, 1957, Serial No. 45,788

Term of patent 14 years

(Cl. D2—3)

Fig. 1 is a front view of an operating handle for a beverage dispenser showing my new design.

Fig. 2 is a side view of the handle of Figure 1.

Fig. 3 is a bottom view of the handle of Figure 1.

The phantom line showing of a support in Figs. 2 and 3 is for illustrative purposes only.

I claim:

The ornamental design for an operating handle for a beverage dispenser, as shown and described.
